W. T. PEPPER.

Seed Planter.

No. 17,582.

Patented June 16, 1857.

UNITED STATES PATENT OFFICE.

WILLIAM T. PEPPER, OF RISING SUN, INDIANA.

IMPROVEMENT IN CORN-PLANTERS.

Specification forming part of Letters Patent No. 17,582, dated June 16, 1857.

To all whom it may concern:

Be it known that I, WILLIAM T. PEPPER, of Rising Sun, in the county of Ohio and State of Indiana, have invented new and useful Improvements in Corn-Planters; and I hereby declare the following to be a full and exact description thereof, reference being had to the accompanying drawings, making part of this specification.

The object of my invention is to produce a machine which, with as great rapidity as a field can be "laid off" in one direction for planting, will plant in hills at points desired by the operator, with sufficient accuracy to enable it to be cultivated in both directions, and will cover the seed as well as it can be done by hand.

In the accompanying drawings, Figure 1 is a side view of the machine. Fig. 2 is a vertical section of the seed-box, exhibiting the dropping and covering mechanism. Fig. 3 is a transverse section of a portion of the ground-wheel through the point $x x$, Fig. 1.

a is a large ground-wheel, provided with flanges on its periphery, two large ones, $B B'$, on the outside, and a number of smaller ones, b , intervening, as shown in Fig. 3. These flanges, as the wheel rotates, carry up a portion of the fresh earth uncovered by the plow c , which earth, being intercepted by scrapers d , is removed from the wheel, deposited in the trough e , and thereby conveyed into the upper apartment, F , of the seed-box. A plate, h , parallel with the periphery of the wheel, extending from one to the other of the outside flanges, $B B'$, and from near the ground to within a short distance of the scrapers d , is kept in contact with the edges of the smaller flanges by means of a spring, i , and serves to prevent the earth falling from the wheel before reaching the scrapers d .

j is a cogged rack, journaled in the rear beam, k , and confined on the seed-box l by staples, which allow it a sliding play longitudinally of said box. This rack, by gearing in a cog-wheel, m , imparts at every vertical motion of the seed-box a reciprocating circular motion to the measuring mechanism, which consists of a small wheel, n , with a cavity, o , in its periphery adjustable in depth, so that it may be adapted to receive any amount of seed required. The seed falling into the conductor p , which passes under the wheel n , is thereby conducted onto the lower floor, $g g'$, of the seed-box. A

pair of brushes, $q q'$, one attached to the bottom of the hopper and the other to the measuring-wheel, prevent a grain of corn from catching and thereby impeding the motion of the wheel. The rack j , gearing also with a pair of cogged segments, $r r'$, at every motion of the seed-box, opens the trap-doors $f f'$, which compose the upper floor of the seed-box, on which earth is deposited, as explained. A precisely similar arrangement on the other side of the box l operates the doors $g g'$, which compose the lower floor of the seed-box, so that the floors of both apartments are opened simultaneously. A sliding gate, s , attached to the rack j closes the way against the ingress of earth while the rack is depressed in the act of planting.

t is a lever by which the plow is raised off the ground, when desired, to enable the machine to pass over obstructions or turn round freely at the end of the row.

The draft-beam u , handles v , attached to the beam k , and the plow-beam w , being separately hinged, can each be raised or depressed without influencing other parts of the machine.

The operation is as follows: A horse being attached at u , and the machine held by the hand of the operator at v , the wheel a , rotating as the machine advances, carries up between the flanges $B b$ a portion of earth, which, being removed from the wheel by the scrapers d , passes down the trough e , and is deposited on the upper floor, $f f'$, of the seed-box.

When it is desired to plant a hill, the rear part of the machine being depressed to bring the seed-box in contact with the ground, while the machine continues to move forward, the lower end of the box remains stationary, bringing it into the position shown by red lines in Fig. 1. At the same time the depression of the rack j closes the entrance to the upper apartment, F , of the seed-box, and, causing the segments $r r'$ and similar segments on the other side of the seed-box to rotate slightly, opens the bottom of both apartments simultaneously and allows the seed contained in the lower one to fall on the ground, while the earth contained in the upper one falls on and covers the seed. At the same time the upper teeth of the rack j , rotating the cog-wheel m , bring the cup o in position to receive seed for the next hill.

Fig. 2 exhibits the relative positions of the various parts of the seed-box at this moment.

The hill being planted, the downward press-

ure of the hand is removed, and a weight, *x*, depressing the front end of the beam *v*, elevates the rear beam, *k*, to which it is attached, and permits the spring *y* to restore the seed-box to its former position, simultaneously closing the bottoms of both apartments, raising the slide *s* to admit the accumulated earth, and emptying the portion of seed into the conductor *p*, by which it is deposited in the lower apartment, *G*, of the seed-box, in readiness for the next hill.

It is not expected that this machine will operate with equal facility in all descriptions of soil; but it is admirably adapted to the friable alluvial soil of the West.

The following are some of its peculiar advantages:

First, the bottom of the seed-box being within a few inches of the ground, and being by an instantaneous action brought into contact with the ground, and held stationary thereby during the act of planting, the operator is enabled to plant with great accuracy in any desired spot, and the seed is dropped without the slightest scattering or irregularity.

Secondly, a regular quantity of the most fri-

able mold is lightly deposited on the seed, the effect being very similar to that produced by careful seed-planting by hand.

I claim as new and of my invention herein—

1. The arrangement of the flanges *B b* on the periphery of the wheel *a*, when used in connection with the plate *h*, scrapers *d*, and receiving or conducting spout *c*, or their equivalents, the whole being arranged and operating in the manner substantially as and for the purposes set forth.

2. The rocking seed-box *l*, having its lower end held stationary during the act of planting by contact with the ground, and operated automatically by the power by which the machine is drawn forward, in the described combination with the falling floors *f f'*, *g g'* and seed measuring and delivering mechanism *n o p*, operated by means of racks *j* by depressing the box against the ground, as set forth.

In testimony of which invention I hereunto set my hand.

W. T. PEPPER.
